UNITED STATES PATENT OFFICE.

PATRICK F. HANLEY, OF HOMESTEAD, PENNSYLVANIA.

ROLLING-MILL.

SPECIFICATION forming part of Letters Patent No. 417,484, dated December 17, 1889.

Application filed October 24, 1889. Serial No. 328,089. (No model.)

To all whom it may concern:

Be it known that I, PATRICK F. HANLEY, a citizen of the United States, residing at Homestead, in the county of Allegheny and State of Pennsylvania, have invented or discovered a certain new and useful Improvement in Rolling-Mills, of which improvement the following is a specification.

In Letters Patent No. 352,748, dated November 16, 1886, and in applications numbered and filed as follows: Serial No. 296,571, January 17, 1889, and Serial No. 321,261, August 19, 1889, respectively, are described and claimed certain mechanisms for shifting the table-supporting carriages and for raising and lowering the tables employed in rolling-mill plants for feeding the material to be operated on to the rolls.

The invention described herein relates to certain further and additional improvements in mechanism for effecting such movements.

In general terms, the invention consists in the construction and arrangement of mechanical devices or elements, all as more fully hereinafter described and claimed.

In the accompanying drawings, forming a part of this specification, Figure 1 is a plan view of a rolling-mill having my improved carriage-shifting mechanism applied thereto. Fig. 2 is a similar view of a mill, showing a modified arrangement of the carriage-shifting mechanism. Fig. 3 is a plan view of a rolling-mill having my improved table-lifting mechanism applied thereto; and Fig. 4 is an end elevation of one of the carriages and tables, showing the table-lifting mechanism.

In the practice of my invention two pairs of rails 1 and 1^a are arranged on each side of the rolls A, parallel with the axes of said rolls. On these rails are mounted suitable trucks having frames 2 2^a secured thereto, said frames and trucks forming carriages for the tables 3 3^a. The tables 3 3^a consist, as set forth in said Letters Patent and applications hereinbefore referred to, in side plates having feed-rolls mounted therein, said rolls being driven by a suitable train of gearing secured to the ends of said rolls. The tables are pivotally mounted at or near their outer ends upon the carriages, so as to permit of the vertical adjustment of the ends of the tables adjacent to the rolls A. In order to

effect this vertical adjustment of the table, an arm 4 is secured to cross-bar 5 at the inner end of the table, as shown in Figs. 3 and 4, 55 said arm extending down between the sides of the frame of the carriage and resting at its lower end, which is preferably provided with an anti-friction roll 6, upon a wire rope 7. This rope is secured at one end to a post 8 or 60 other suitable anchor and passing over anti-friction rolls on the upper ends of standards 10, attached to the sides of the carriage-frame 2, and under the arm 4 is attached at its opposite end to a drum 11. This drum and the 65 post or anchor 8 are so located at or beyond the opposite ends of the lateral traverse of the carriage as not to interfere with the movements thereof. The arm 4 and standards 10 are so proportioned as to their relative lengths 70 that when the rope is tightened by the rotation of the drum, so that the portion between the standards is approximately straight, the table will be at the desired limit of its upward movement. The shaft of the drum 11 75 is provided with a pinion 12, intermeshing with a rack-bar 13, secured to the piston-rod of the fluid-pressure cylinder 14, whereby said drum is rotated.

In the arrangement shown in Fig. 3 both drums 11 and 11^a are actuated simultaneously by the same cylinder, as it is desired that simultaneous and equal movements of both tables 3 3^a should be had; but it will be readily understood that the drums may be 85 actuated by independent cylinders. The arrangement of the rope over the standards 10 and under the arm 4, without any attachment to said parts, permits of the free lateral movements of the carriage without changing the 90 vertical position of the table.

For shifting the carriage laterally, drums 15 are mounted on the carriage, near the ends thereof, and around said drums are passed two or three turns of ropes 16, whose ends 95 are attached to posts 17 or other suitable anchors located at points a little beyond the limits of traverse of the carriage. On the shafts of the drums 15, which are mounted in suitable bearings on the carriage, are keyed pinions, (shown in dotted lines in Fig. 1,) which intermesh with rack-bars 18, connected to the piston of the cylinder 19, said cylinder being secured to the carriage between the 100

drums, and provided with piston-rods extending through the heads of the cylinder. By the movements of the piston in the cylinder the drums may be rotated in either direction, 5 thereby winding the ropes on one side of the carriage and moving the latter in that direction while the ropes on the opposite side are unwound.

In the arrangement in Fig. 1 the carriages 10 2 2^a are moved independently; but as it is desirable at times to shift both carriages simultaneously provision is made therefor by placing drums 19 19^a at one end of the lateral movement of the carriages, and around these 15 drums are passed two, three, or more turns of the ropes 20 21 and 20^a 21^a, respectively, as shown in Fig. 2. The rope 20 on one side of the drum is passed around a guide-pulley 22 and its end secured to the side of the carriage, at the inner end thereof, while the portion 20 of the rope leading from the opposite side of the drum is passed around guide-pulleys 23 and 24 and its end connected to the opposite side of the carriage, at or near the 25 outer end thereof. The rope 21 is correspondingly arranged—that is to say, the portion leading out from one side of the drum is passed around the guide-pulleys 25 and 26 and its end secured to the inner end of the 30 carriage, while the other portion of said rope is passed around the pulley 27 and its end secured to the outer end of the carriage. It will be observed that the ends of each of the ropes 20 and 21 are attached to opposite sides 35 of the carriage at opposite ends thereof, and that the ropes are so wound around the drum that on the rotation of the latter the portions of the rope attached to one side of the carriage will be wound up, while the portions 40 connected to the opposite side are paid out. The ropes 20^a 21^a for operating the carriage 2^a are similarly arranged. The drums 19 19^a have pinions 28 28^a keyed to their shafts, said pinions engaging rack-bars 29 29^a, which are 45 connected to the piston-rods of the fluid-pressure cylinder 30. The racks are so arranged that by their movement in one direction by the piston of the cylinder 30 the drums will be so rotated as to shift the carriages equally in the same direction.

It will be understood that the means shown in Figs. 3 and 4 for raising and lowering the tables can be used in connection with either of the means hereinbefore described or with 55 any other suitable means for shifting the carriages laterally, and also that any suitable means for adjusting the tables vertically can be employed in connection with the mechanism shown in Figs. 1 or 2 for moving the tables laterally.

The lateral movement of the carriage 2^a simultaneously with the carriage 2 can be effected by connecting the carriage 2^a to the carriage 2 in the manner shown in dotted lines in Fig. 1, the carriage 2 being the prime 65 motor and operated in the manner shown in Fig. 1 or in any other suitable manner.

As shown in Fig. 1 by dotted lines, ropes 31 and 32 are connected to the carriage 2, and leading therefrom in opposite directions are 70 passed around guide-pulleys 33 33^a, 34 34^a, and 35 35^a, and pass to the carriage 2^a from opposite sides thereof. The arrangement of ropes for the concomitant movement of the carriages 2 2^a is shown as connecting the inner 75 ends of the carriages; but it will be understood that a similar connection is formed between the outer ends of the carriages. In lieu of connecting the ropes 31 and 32 to the carriage 2, they may be connected to the drums 15 in said carriage.

I claim herein as my invention—

1. In a rolling-mill plant, the combination of a reversible rotating drum, a flexible connection extending in opposite directions from 85 the drum, one of said members being fixed and the other movable, and a laterally-movable carriage coupled to the flexible connection, substantially as set forth.

2. In a rolling-mill plant, the combination 90 of a laterally-movable carriage, a reversible rotating drum mounted on said carriage, a rope or other flexible device passing around said drum and extending in opposite directions from said drum and having its ends secured to stationary posts or anchors, substantially as set forth.

3. In a rolling-mill plant, the combination of a laterally-movable carriage, a table pivoted thereto, a reversible rotating drum, and 100 a rope passing over standards or supports on the carriage and under an arm on the table, one end of said rope being connected to the drum and the other end to stationary posts or anchor on the side of the carriage opposite 105 the drum, substantially as set forth.

4. In a rolling-mill plant, the combination of laterally-movable carriages, reversible rotating drums, ropes passing around said drums and coupled to the carriages, whereby 110 simultaneous movements of both carriages are effected, substantially as set forth.

In testimony whereof I have hereunto set my hand.

PATRICK F. HANLEY.
